UNITED STATES PATENT OFFICE.

GUSTAVE C. C. VOGT, OF LIMOGES, FRANCE.

DESIGN FOR A COVERED DISH.

SPECIFICATION forming part of Design No. 26,430, dated December 22, 1896.

Application filed November 12, 1896. Serial No. 611,891. Term of patent 14 years.

To all whom it may concern:

Be it known that I, GUSTAVE C. C. VOGT, a citizen of France, residing in the city of Limoges, in the Republic of France, have invented and produced a new and original Design for a Covered Dish, of which the following is a specification.

The leading features of my design are a covered dish the body of which is bowl-shaped and provided around its lower portion with a foliate wreath or band and above the same with crockets or like ornaments, and the cover of which has shell-like ornamentalations at its center and representations of sprigs or tendrils at either side of the shell-like formations.

Referring to the drawings, A indicates the bowl-like body of the covered dish, which is provided with an inwardly-tapering base a, the lower edge of which is formed with heliciform curves or volutes b, above which tapering base the body of the dish is provided with foliations C in the form of a band or wreath encircling the body. Above the wreath or foliations C the body A of the dish is provided at each side with crockets or similarly-shaped ornamentalations D, extending in opposite directions, while the rim a' of the body is sealed, and downwardly-extending flutes, ribs, or corrugations a'' are formed on the body below the rim. 30

The circular cover E of the dish is provided at one side with a recess e, the edge of which is ornamented by foliations e', while at the center of the cover E are two shell-like formations F, arranged back to back, from each side of which extend sprigs or tendrils f. 35

What I claim is—

The design for a covered dish substantially as shown and described. 40

In testimony that I claim the foregoing as my invention I have signed my name in presence of two subscribing witnesses.

GUSTAVE C. C. VOGT.
